UNITED STATES PATENT OFFICE.

GEORGE H. BABCOCK, OF PLAINFIELD, NEW JERSEY.

DESIGN FOR A ROOFING-TILE.

SPECIFICATION forming part of Design No. 20,401, dated December 16, 1890.

Application filed May 14, 1890. Serial No. 351,808. Term of patent 14 years.

To all whom it may concern:

Be it known that I, GEORGE H. BABCOCK, a citizen of the United States, residing at Plainfield, in the county of Union and State of New Jersey, have invented and produced a new and original Design for Roofing or Sheathing Tiles, of which the following is a specification, reference being had to the accompanying drawings, forming a part thereof.

10 The design relates to a clay or other tile in which the ornamental effects are produced by the outline of the tile, by the surface ornamentation thereof, and by the conjunction of the two.

15 The design consists of a tile the surface whereof is ornamented by a curved edge band alone and in conjunction with the shape of the tile.

20 In the accompanying illustrations, Figure 1 is a face view of a tile of the new design; and Fig. 2 illustrates a number of such tiles in an assembled condition laid in quincunx order, illustrating the effect of the shape or outline and the surface ornamentation of the tile when assembled with other like tiles.

25 The design relates particularly to the exposed or lower face of the tile, its upper portion partaking of various shapes, according to the particular mode employed in assembling like tiles with one another.

30 As illustrated, the tile has diagonal upper

sides *a b*, which bear upper flanges. The lower or exposed portion of the tile is shaped to impart a cone-like form thereto, with a plain surface *A*. The cone-like form, however, is imparted by two convex curves *c d* and two smaller convex curves *c' d'*, which meet each other and terminate in a point. The surface ornamentation consists of a band *B*, extending along the lower edge of the tile and curved 40 to correspond to the convex curved outline of the tile. The inner edge of the band *B* is shown as beveled to the plain surface of the tile, as indicated by the lines *s s*. The surface of the band may itself be ornamented, as 45 by the heads or beads *n*.

It may be stated that when a number of such tiles are assembled as in Fig. 2 and laid in quincunx order the bands of contiguous tiles intersect one another, as at *x*, 50 forming a diagonal series of bands formed of a series of convex curves, each curve made up of a larger curve, as *c* or *d*, and a smaller curve, as *c' d'*.

What is claimed is—

55 The design for a tile, substantially as described and shown.

GEO. H. BABCOCK.
